To all whom it may concern:

Be it known that I, MILDRED C. ornamental strips contrasting with the ground color of the blouse.

Figure 1 is a front view of a blouse, showing my new design.

Figure 2 is rear view of the blouse shown in Figure 1.

Figure 3 is an enlarged rear view of one of the cuffs and part of the sleeve showing the ornamental arrangement of contrasting strips.

I claim:

The ornamental design for a blouse, substantially as shown and described.
